(57) **CLAIM**

The ornamental design for a piercing nut as shown and described.

DESCRIPTION

Figure 1.1 is a front view of a first embodiment of a piercing nut.

Figure 1.2 is a right-side view of the first embodiment.

Figure 1.3 is a top view of the first embodiment.

Figure 1.4 is a bottom view of the first embodiment.

Figure 1.5 is a perspective view of the first embodiment.

Figure 1.6 is a cross-sectional view of the first embodiment taken along line 1.6 in Figure 1.1.

Figure 1.7 is a cross-sectional view of the first embodiment taken along line 1.7 in Figure 1.1.

Figure 1.8 is a cross-sectional view of the first embodiment taken along line 1.8 in Figure 1.3;

Figure 2.1 is a front view of a second embodiment of a piercing nut.

Figure 2.2 is a right-side view of the second embodiment.

Figure 2.3 is a top view of the second embodiment.

Figure 2.4 is a bottom view of the second embodiment.

Figure 2.5 is a perspective view of the second embodiment.

Figure 2.6 is a cross-sectional view of the first embodiment taken along line 2.6 in Figure 2.1.

Figure 2.7 is a cross-sectional view of the first embodiment taken along line 2.7 in Figure 2.1.

Figure 2.8 is a cross-sectional view of the first embodiment taken along line 2.8 in Figure 2.3;

Figure 3.1 is a front view of a third embodiment of a piercing nut.

Figure 3.2 is a top view of the third embodiment.

Figure 3.3 is a bottom view of the third embodiment.

Figure 3.4 is a perspective view of the third embodiment.

Figure 3.5 is a cross-sectional view of the first embodiment taken along line 3.5 in Figure 3.1.

Figure 3.6 is a cross-sectional view of the first embodiment taken along line 3.6 in Figure 3.1.

Figure 3.7 is a cross-sectional view of the first embodiment taken along line 3.7 in Figure 3.2.

(Continued)

The left-side view and the rear view of the first embodiment are omitted as they appear identical to the right-side view shown in Figure 1.2 and the front view shown in Figure 1.1, respectively.

The left-side view and the rear view of the second embodiment are omitted as they appear identical to the right-side view shown in Figure 2.2 and the front view shown in Figure 2.1, respectively.

The right-side view, the left-side view, and the rear view of the third embodiment are omitted as they appear identical to the front view shown in Figure 3.1.

The broken lines represent portions of the structure that form no part of the claim.
